UNITED STATES PATENT OFFICE

RONALD BENFIELD, OF CALGARY, ALBERTA, CANADA

SELF STARTER

Application filed August 12, 1929. Serial No. 385,446.

My invention relates to improvements in self starters for automobile and other internal combustion engines, and the object of my invention is to provide a simple device for such purposes and one in which the possibility of its becoming inoperative is reduced to a minimum.

I attain these objects by the mechanism illustrated in the accompanying drawings, in which—

Fig. 1 shows a side view of the device in part section.

Fig. 2 shows an end view of the same.

Similar numbers refer to similar parts throughout the several views.

1 is a cylinder closed at one end with the bearing flange 2 and is rigidly mounted on said flange by set screws 3. Pinion spur wheel 4 is rigidly attached to flange 2 on its outer face and these bear slidably on shaft 5, said shaft being the extended end of armature shaft of electric driving prime-mover 6, and projects into cylinder 1 through its closed end and terminates at the open end of cylinder 1 with a detachable collar 7 securely fitted and pinned to said shaft 5 as shown by collar pin or bolt 5a. Helical compression spring 8 has one end attached to the inside face of collar 7 at a point towards the periphery of said collar. This spring concentrically encloses that portion of shaft 5 inside the cylinder and has its other end securely affixed to the interior face of flange 2. Flexible steel woven cable 9 concentrically encloses shaft 5 within cylinder 1 and has one end securely attached to interior face of collar 7, the other end being affixed to the interior face of flange 2 and is itself concentrically enclosed within helical spring 8. The object of such an arrangement of spring and cable is that as the bell-crank starter lever 10 is depressed against the retaining spring 11, compression spring 8, reacting against collar 7 forces spur pinion 4 into mesh with teeth of fly-wheel ring gear 12 connected directly or otherwise with the engine to be started, or into such a position that the teeth will slip into mesh so soon as electric current is subsequently applied to the starting motor and cable 9 grips around

shaft 5, the spur revolving a minimum amount to engage the teeth of 12 under the influence of compressed spring 8. The correct number of turns of cable 9 around shaft 5 assures the retention of spur 4 with gear 12. Cable 9 acts as a shock-absorber intermediate the driving and driven motors, its function as such being to gradually grip the revolving shaft 5 by means of the leverage at its winding end and the fact that it is anchored to an independent element of the apparatus at its opposite end. In its inoperative position cable 9 is deflexed loosely around shaft 5 and sufficient interval is allowed during the winding up action to absorb any possible shock on the motor, as the armature gains speed, and also on the teeth of spur wheel 4 and gear wheel 12. Lever 10 is forked at its lower end to saddle over shaft 5 and is mounted on fulcrum bracket 13 attached to principal supporting bracket 14, on which bracket 14 is also mounted the motor 6 and all other starter mechanism described, with the exception of gear wheel 12. 15 is a short metal safety strip attached to one end of cable 9 and intermediate the cable and flange 7, being inserted to localize a possible overload breakdown of the cable or a possible breakdown due to backfire. On release of pressure on lever 10 electric current is disconnected, spur wheel 4 is disengaged from gear wheel 12 by the tension of spring 11 and at the same time spring 8 uncoils and assists and assures the release of cable 9 from shaft 5. When the engine starts to function, through the medium of spur 4 engaging gear wheel 12 and since spur 4 is greater in diameter than gear wheel 12, spur 4 will accelerate over shaft 5 in speed resulting in the unwinding of cable 9 and allowing spring 8 to uncoil to normal, which effect will rotate shaft 5 up to the speed of spur 4 until such time as spur 4 is released from gear wheel 12 by the action of lever 10. Arrow in Fig. 1 indicates direction of applied pressure for starting; the arrow in Fig. 2 indicates direction of rotation of motor shaft.

I am aware that prior to my invention starter devices have been invented with spur wheels travelling on threaded shafts and with

housing to contain the various elements of which these devices consist, but what I do claim as my invention and desire to secure by Letters Patent is:—

5. 1. The combination in a self starter of a motor driven shaft with a collar fixed thereto, a combined flange and spur wheel running free on said shaft and connected to said fixed flange by a flexible shock-absorbing cable enclosing said shaft, a large diameter helical spring enclosing said shaft and spiral cable attached in similar manner to said free running flange and combined spur wheel at one of its ends and to fixed collar at its opposite end, a bell-crank forked lever to regulate the lengthwise travel of the spur wheel on its shaft for engagement with and disengagement from a gear on the engine to be started, all as described.
10. 2. The combination in a self starter of a motor driven shaft with a collar fixed thereto, a combined flange and spur wheel running free on said shaft and connected to said fixed flange by a flexible shock-absorbing cable enclosing said shaft, a large diameter helical spring enclosing said shaft and spiral cable attached in similar manner to said free running flange and combined spur wheel at one of its ends and to fixed collar at its opposite end, a bell-crank forked lever to regulate the lengthwise travel of the spur wheel on its shaft for engagement with and disengagement from a gear on the engine to be started, a metal safety strip interposed between said flexible cable and one of its end connections and of lesser tensile strength than said flexible cable.
15. 3. The combination in a self starter of a motor driven shaft with a collar fixed thereto, a combined flange and spur wheel running free on said shaft and connected to said fixed flange by a flexible shock-absorbing cable enclosing said shaft, a large diameter helical spring enclosing said shaft and spiral cable attached in similar manner to said free running flange and combined spur wheel at one of its ends and to the fixed collar at its opposite end, a bell-crank forked lever to regulate the lengthwise travel of the spur wheel on its shaft for engagement with and disengagement from a gear on the engine to be started, a metal safety strip interposed between said flexible cable and one of its end connections and of lesser tensile strength than said flexible cable, a cylindrical housing bearing on said shaft to contain the spring and tension cable parts of this device, all as described and set forth in the specification and drawings.

RONALD BENFIELD.
